UNITED STATES PATENT OFFICE.

DE LOSS McCOMAS, OF CALHOUN, MISSOURI.

IMPROVEMENT IN CAR-COUPINGS.

Specification forming part of Letters Patent No. 118,957, dated September 12, 1871.

To all whom it may concern:

Be it known that I, DE LOSS McCOMAS, of Calhoun, in the county of Henry and in the State of Missouri, have invented certain new and useful Improvements in Car-Coupling; and do hereby declare that the following is a full, clear, and exact description thereof, reference being had to the accompanying drawing and to the letters of reference marked thereon making a part of this specification.

The nature of my invention consists in the construction and arrangement of a car-coupling, as will be hereinafter more fully set forth.

In order to enable others skilled in the art to which my invention appertains to make and use the same, I will now proceed to describe its construction and operation, referring to the annexed drawing, in which—

Figure 1 is a side view, and Fig. 2 a longitudinal vertical section of my car-coupling. Fig. 3 is a front view of one draw-head, and Fig. 4 is a similar view, showing the means for uncoupling.

A represents the draw-head, on the under side of which is attached a metal box, B, the bottom of said box being inclined upward and toward the rear from the front. In the box B is a false bottom, C, curved, as shown in Fig. 2, which acts as a guide for the coupling-link. On the under side of the head A, at or rather within the mouth of the box B, is a forked bar, D, which is open at its lower end, and immediately in front of said bar is attached a spring, E, bent in the peculiar form shown in Fig. 3, its ends projecting a trifle beyond the sides of the box. The coupling-link G consists of a bar with a round head or ball on each end, as shown.

In coupling, the ball of the link slides up upon the guide C until the bar enters the forked bar D and, at the same time, forces the two arms of

the spring apart and passes above those portions of the spring which come so close together. This spring thus holds the coupling-link from dropping out while the whole strain comes upon the bar D, which may be made in any suitable manner so as to withstand the necessary strain.

To uncouple, I attach, as shown in Fig. 4, a chain, a, to each end of the spring E, and carry the same around a pulley, b, in the platform, the other end of said chain being attached to a lever, d, pivoted on the platform. The two levers d d are then connected by a foot-piece, e, so that by pressing down on the same the ends of the spring E are separated still further, which permits the coupling-link to drop down, and thus uncoupling the cars. On freight-cars the ends of the chains a a should be connected to rods running up the end of the car, and said rods attached to a foot-lever on top of the car.

Having thus fully described my invention, what I claim as new, and desire to secure by Letters Patent, is—

1. The box B, with guide C, the forked bar C, and spring E, all constructed and arranged, substantially as shown and described, with the draw-head of a railroad-car, for the purposes herein set forth.
2. In combination with spring E, the chains a a, levers d d, and foot-piece e, or their equivalents, arranged substantially as shown and described, and for the purposes herein set forth.

In testimony that I claim the foregoing I have hereunto set my hand this 17th day of February, 1871.

DE LOSS McCOMAS.
